VEHICLE FRAME CONSTRUCTION

Alfred H. Haberstump, Detroit, Mich., assignor to
The Murray Corporation of America, a corpora-
tion of Delaware

Application September 30, 1932, Serial No. 635,617

4 Claims. (Cl. 296—28)

My invention relates to vehicle bodies and particularly to a roof rail therefor which is of roll section constructed to interfit with the vehicle framing elements to constitute a unit structure which is exceedingly rigid, readily assemblable and a material advancement in the art over roof rails employed heretofore.

The main objects of my invention are: to provide a roof rail of closed section which may be rolled from a unit strip of material to form flanges and channel portions which are complementary to the vehicle body framing which are joined thereto; to provide a roof rail of box section having flanges projecting on opposite sides thereof to which the body header and pillar framing are secured to form the top skeleton structures of the vehicle body; to provide a header and pillar reinforcing member for a header or pillar element with engaging flanges which cooperate with flanges of a metal roof rail of box section, all of which are united to form a rigid frame construction; and to provide a frame structure for a vehicle body which is simple in construction, which is readily assemblable and which is economical of manufacture.

Other objects and features of novelty of my invention will be either specifically pointed out or will become apparent when referring for a better understanding of my invention to the following description in conjunction with the accompanying drawing, wherein:

Figure 1 is a broken plan view of vehicle roof rails embodying features of my invention;

Fig. 2 is an enlarged, broken end view of the structure illustrated in Fig. 1;

Fig. 3 is a sectional view of the structure illustrated in Fig. 1, taken on the line 3—3 thereof;

Fig. 4 is an enlarged broken view of the structure illustrated in Fig. 1; and

Fig. 5 is an enlarged sectional view of the structure illustrated in Fig. 1, taken on the line 5—5 thereof.

It has been the practice in the art to employ roof rails made of wood or metal which are secured to the paneling, pillar and header structure in a predetermined manner to form the body framing. While this construction produced a satisfactory body, certain features of the wood and metal rails were objectionable, requiring considerable labor in assembly and, because of the position of the heavy rails at the top of the body, raised the center gravity thereof which increases the hazards of the resulting vehicle turning over when tilted.

In practicing my present invention, I provide

a roof rail which is made of strips of thin material which are rolled into a box section structure which is embodied with considerable strength per unit weight. The strip is so rolled as to provide a channel formation on one side formed by two projecting flanges at the top and bottom of the rail. A single flange is formed on the opposite side of the rail by the junction of the ends of the strip. The flanges are double the thickness of the material and provide strength to prevent their distortion when strained. The remainder of the material forming the body portion of the rail is spaced apart to form a box section structure.

Referring to the figures, I have illustrated a roof rail 6 which is secured to a header 7 and pillars 8 and 9 by rivets, although it is to be understood that welding, brazing, bolts or other securing means may be utilized for securing the roof rails to the supporting elements. The roof rail 6 is illustrated in an enlarged section in Fig. 5, being made of a strip of material which is rolled in a manner to produce the box structure 11, the oppositely disposed flanges 12 and 13 and the flange 14 which is formed by the edges of the strip which are mated together and welded or otherwise secured to form the unit rail construction. The rail thus provided embodies the flanges 12, 13 and 14 by which attachment is made to the pillars and header of the body, and, since they are twice the thickness of the sheets forming the rail, can withstand considerable stress to which they may be subjected at the attaching points.

The channel opening 15, provided between the flanges 12 and 13, may be utilized for receiving a tacking strip to which the inner finishing elements of the body may be readily secured. The box structure provided on the main portion of the header, has considerable strength, substantially the maximum strength which can be obtained for the size of the rail and the thickness of material. A downwardly extending lip 16 is provided on the flange 14 for extending over and engaging the flanges provided on the end of the pillar or header to strengthen the joint therebetween. The lip also forms a means for positioning and securing the lower edge of the roof panels to the framing, as will be described hereinafter.

In the co-pending application of O. F. Graebner, Ser. No. 624,031, filed July 22, 1932, and assigned to the assignee of the present invention, a body pillar is shown, described and claimed, connected to a top rail which embodies features

of the present invention. The pillar is similar to the pillar 8 illustrated in Fig. 2, having a notch 18 in its top end to receive the roof rail 6. The end is flanged at 19, laterally of the pillar, following the contour of the notch to closely engage the lower and central flanges of the rail. A similar construction is illustrated in Fig. 4, effected between the engagement of the pillar 9 with the rail. The pillar is similarly formed with a notch 18 and flanges 19 at its end, by which, securement is obtained between the pillar and rail. Rivets 21 may be utilized for securing the flanges 19 of the pillar to the flanges of the rail or other means may be employed such as welding or brazing to form a unit joint therebetween.

In Figs. 2 and 3, I have illustrated the connection between the rolled roof rail and the front body pillar 8 and header 7 wherein the header is suitably flanged at 22 for engagement with the top flange 12 of the roof rail to which it is secured by rivets 23 or other suitable means. The side edges of the header 7 are provided with rearwardly extending flanges 24 which engage the web portion 13 of the roof rail to which it is secured by means of rivets 23 or other securing means. In like manner the reinforcing portion 25 of the front pillar 8 is of arcuate shape extending rearwardly at its upper end in engagement with the flange 13 of the roof rail to which it is secured by suitable securing means. In a similar manner the side ends of the header extend downwardly and outwardly in engagement with the flange 14 which is likewise secured by rivets or similar means.

Referring more particularly to Fig. 5, I have illustrated, enlarged, a section of the roof rail and panel at the door opening. The panel 26 slopes downwardly and is flanged inwardly and downwardly to form a lip which engages with the lip 16. The projecting end of the flange 14 positions the panel 26 relative to the frame and forms a securing means with the lip 16 for retaining the panel in position.

At the door opening a finish molding 27 encompasses the lower side of the flange 14, the lip 16 and the lip on the panel 26. The molding receives and retains the weather strip 28 in position below the flange of the panel 27, for sealing a door against the entrance of dust and moisture. The molding and weather strip are secured in position by screws 29 or other suitable securing means.

Referring to Fig. 1, it will be noted that the rolled roof rails are constructed to extend over the greater portion of the length of the body but not the whole portion, the remaining portion thereof being formed of wood rail members 26 which are secured in extension of the metal rail section. It is to be understood that it is within the contemplation of my invention to extend the rolled roof sections the continual length of the car body to eliminate the wood extending portion 26, to provide unit rails made entirely of metal.

It will be noted that the particular rolled section of the rail provides many desirable features, such as added strength in the presence of decreased weight, the presence of flanges positioned to be readily attached to ends of various cross braces and pillars and also a channel 15 formed by the flanges 12 and 13 for receiving a wood tack-

ing strip to which the inner finish material is secured. The box section structure 11 and the double thickness of material in the flanges 12, 13 and 14 of the strip, add considerable strength thereto which permits the use of lighter gauge material and thereby reduces the weight of the resultant rail which tends to lower the center of gravity of the body. By having flanges 12 and 13 extending on the inner side of the rail and the flange 14 disposed centrally of the height of the rail and outwardly of the body, attaching ledges are provided in position to be readily engaged by flanges on the elements to which the rail is to be attached, or to be attached to the rail, which materially strengthens the element and the rail rather than weakens it as oftentimes occurs.

While I have described and illustrated but a single embodiment of my invention it will be apparent to those skilled in the art that various changes, omissions, additions and substitutions may be made therein without departing from the spirit and scope of the invention, as set forth in the accompanying claims.

I claim:

1. A rolled roof rail having a box section and a channel section formed by overlapping portions of the material which constitute flanges of the channel section, a flange projecting medially between the first said flanges from the box section on the opposite side from said channel which terminates in an extremity of L-shape, and a roof panel having a portion engaged by said L-shaped extremity for positioning said panel, 30

2. A rolled roof rail having a box section and a channel section formed by overlapping portions of the material which constitute flanges of the channel section, a flange projecting medially between the first said flanges from the box section on the opposite side from said channel which terminates in an extremity of L-shape, a roof panel 35 having a portion engaged by said L-shaped extremity for positioning said panel, and a finish strip covering said last flange and the junction of the extremity and panel to form a finish therefor at the door opening.

3. A rolled roof rail having a box section and a channel section formed by overlapping portions of the material which constitute flanges of the channel section, a flange projecting medially between the first said flanges from the box section on the opposite side from said channel which terminates in an extremity of L-shape, a roof panel 50 having a portion engaged by said L-shaped extremity for positioning said panel, a finish strip covering said last flange and the junction of the extremity and panel to form a finish therefor at the door opening, and a sealing element supported by said strip in a position to be engaged by a door.

4. A roof rail rolled from a unit strip of material to form a box section construction of single thickness, two flanges extending from said box section construction of double the thickness of material and spaced apart to form a channel construction with one side of said box section, the sides of said strip opposite to said channel and medially thereof forming a flange of double thickness of material and a downwardly extended flange on said last flange disposed inwardly from the edge thereof.

ALFRED H. HABERSTUMP. 70
